(57) **CLAIM**

An ornamental design for a tie tail cut-off shield, as shown
and described.

DESCRIPTION

FIG. 1 is a perspective view of the first embodiment of the
tie tail cut-off shield;

FIG. 2 is a right side elevation view thereof;

FIG. 3 is a left side elevation view thereof;

FIG. 4 is a top plan view thereof;

FIG. 5 is a front elevation view thereof;

FIG. 6 is a back elevation view thereof; and the bottom of
the tie tail cut-off shield is unornamented.

FIG. 7 is a perspective view of the second embodiment of
the tie tail cut-off shield;

FIG. 8 is a right side elevation view thereof;

FIG. 9 is a left side elevation view thereof;

FIG. 10 is a top plan view thereof;

FIG. 11 is a front elevation view thereof; and the back and
bottom of the tie tail cut-off shield is unornamented.

FIG. 12 is a perspective view of the third embodiment of the
tie tail cut-off shield;

FIG. 13 is a right side elevation view thereof;

FIG. 14 is a left side elevation view thereof;

FIG. 15 is a top plan view thereof;

FIG. 16 is a front elevation view thereof;

FIG. 17 is a back elevation view thereof; and the bottom of
the tie tail cut-off shield is unornamented.

FIG. 18 is a perspective view of the fourth embodiment of
the tie tail cut-off shield;

FIG. 19 is a right side elevation view thereof;

FIG. 20 is a left side elevation view thereof;

FIG. 21 is a top plan view thereof;

FIG. 22 is a front elevation view thereof;

FIG. 23 is a back elevation view thereof; and the bottom of
the tie tail cut-off shield is unornamented.

FIG. 24 is a perspective view of the seventh embodiment of
the tie tail cut-off shield;

FIG. 25 is a right side elevation view thereof;

FIG. 26 is a left side elevation view thereof;

FIG. 27 is a top plan view thereof; and,

FIG. 28 is an end elevation view thereof; and the bottom of
the tie tail cut-off shield is unornamented.

The broken lines are for the purpose of illustrating the
environment of the article only and form no part of the
claimed design. The shading illustrated in the drawings is
provided merely to highlight the contour of the design and
is not intended to be illustrative of any texture or gloss.
